CLAIM

The ornamental design for a cull tag clip, as shown and described.

DESCRIPTION

FIG. 1 is a top perspective view of a cull tag clip showing our design according to a first embodiment;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof;

FIG. 8 is a top perspective view of a cull tag clip showing our design according to a second embodiment;

FIG. 9 is a front view thereof;

FIG. 10 is a back view thereof;

FIG. 11 is a first side view thereof;

FIG. 12 is a second side view thereof;

FIG. 13 is a top view thereof; and,

FIG. 14 is a bottom view thereof.

The dash lines depict portions of the article forming no part of the claimed design.

1 Claim, 14 Drawing Sheets
